STEAM GENERATOR OR WATER HEATER

Edward Frank Spanner, Blackheath, London,
England

Application July 19, 1938, Serial No. 220,093

9 Claims. (Cl. 122—173)

This invention relates to steam generators or water heaters of vertical thimble tube type fired with coal, coke, gas, oil or any other usual fuel fed by hand or mechanical means.

The object of the invention is to reduce the height and cost of direct fired thimble tube boilers and also to improve the overall efficiency of these boilers by maintaining a faster and more consistent speed of flow of the gases throughout the whole depth of the tube nest.

In thimble tube boilers three factors are of great importance in securing high efficiency—

(1) The length of the path the gas is forced to take through the tube nest in passing from furnace to flue.

(2) The total area of heating surface—and—

(3) The speed with which the gas actually passes the surfaces of the thimble tubes.

In thimble tube boilers of known practice it is usual to fit a multiplicity of rows of thimble tubes arranged in a simple staggered pattern. In boilers according to the present invention the diameter of the tube nest is increased, thus enabling more and longer thimble tubes to be fitted per row, and therefore the number of rows to be correspondingly reduced for the same total area of heating surface.

This is of definite advantage in improving the volume of the furnace and reducing the height and cost of the boiler, but it shortens the length of the direct path from bottom to top of the tube nest, and would normally result in loss of efficiency.

The present invention however provides for fitting plain or stepped directional plates in the tube nest these forcing the products of combustion to take a much longer spiral path when passing from the furnace to the flue.

The invention also provides that the pitch of the spiralled directional plates shall be decreased towards the upper end of the tube nest so that the length of travel of the gases is increased as they get cooler, with the result that the speed of flow of the gas does not fall off as otherwise it would, thus maintaining good efficiency throughout the full depth of the tube nest.

In order that the products of combustion shall not pass to the flue along the centre line of the tube nest, the invention provides a heat resisting core hung axially along the centre line of the tube nest, together with means for raising and lowering same.

Further, in thimble tube boilers fitted for firing with coal or coke, it is important that the tube nest shall be kept clear of dust and soot and the

invention provides that a soot-blower may be fitted below or above the tube nest, arranged for operating while the boiler is in service.

Finally the invention provides for the use of spiralled divisional plates or stepped directional plates in vertical steam generators or water heaters arranged to raise stem from two independent sources of heat, one source of heat being a direct-fired furnace surmounted by a thimble tube nest fitted with spiralled divisional plates or stepped directional plates, the other source of heat being a supply of hot waste gas directed into and around a watertube nest attached to the inside of the outer shell so that both ends of the vertical watertubes fitted are open to the annular water and steam space, and so that a passage is provided for hot exhaust gas between the outer shell and an inner circular plate joining the inside edges of the annular tube plates.

In the drawing—

Figure 1 is a vertical section through a large thimble tube boiler in accordance with the invention. A water heater would be similar but with no steam space.

Figure 2 is a vertical section through a small thimble tube boiler in accordance with the invention. A water heater would be similar but with no steam space. Figure 3 is a vertical section through a large thimble tube boiler in accordance with this invention and including also two watertube nests arranged to recover heat from exhaust gases. A water heater would be similar but with no steam space.

Figure 4 is an expansion of a typical tube plate showing spiralled directional plates.

Figure 5 is an expansion of a typical tube plate showing stepped directional plates at varying pitches.

In these figures, an annular water and steam space 1, surrounds a cylindrical furnace plate 2, 40 surrounded by a cylindrical tube plate 3 having expanded into it a multiplicity of rows of thimble tubes 4. In the centre of the tube nest is hung a heat-resisting deflector 5, which is adjustable in the large boiler by the suspension member 6. 45 Plain or stepped spiral directional plates 7 cause the gas to take a spiral path in passing upwards from the furnace 3 to the flue 9. Alternative positions for a steam soot-blower are shown at 10A, 10B, and 10C.

Figure 5 shows how decrease of pitch of the spiral flow is simply obtained by varying the width of the stepped directional plates.

In Figure 3, 11A and 11B are circular watertube nests having vertical watertubes open at 55

each end to the space 1 and arranged to take discharges of exhaust gas from Diesel engines or the like, the gas entering and leaving the tube nests by the openings at 12A and 12B.

5 I claim:—

1. An improved steam generator or water heater of vertical type comprising an annular water and steam space surrounding a cylindrical furnace plate surmounted by a cylindrical tube plate, the tube plate having expanded into it inwardly projecting thimble tubes, a heat-resisting core hung axially along the centre line of the tube nest, and two or more sets of plain spiralled directional plates arranged between the tubes 15 in the tube nest.

2. An improved steam generator or water heater of vertical type comprising an annular water and steam space surrounding a cylindrical furnace plate surmounted by a cylindrical tube 20 plate, the tube plate having expanded into it inwardly projecting thimble tubes, a heat-resisting core hung axially along the centre line of the tube nest, and two or more sets of stepped directional plates arranged in spiral fashion between 25 the tubes in the tube nest.

3. An improved steam generator or water heater of vertical type comprising an annular water and steam space surrounding a cylindrical furnace plate surmounted by a cylindrical tube 30 plate, the tube plate having expanded into it inwardly projecting thimble tubes, a heat-resisting core hung axially along the centre line of the tube nest, together with means for raising or lowering same, and two or more sets of plain spiralled directional plates arranged between the tubes 35 in the tube nest.

4. An improved steam generator or water heater of vertical type comprising an annular water and steam space surrounding a cylindrical furnace plate surmounted by a cylindrical tube 40 plate, the tube plate having expanded into it inwardly projecting thimble tubes, a heat-resisting core hung axially along the centre line of the tube nest, together with means for raising or lowering same, and two or more sets of stepped directional plates arranged in spiral fashion between the tubes in the tube nest.

5. An improved steam generator or water heater of vertical type comprising an annular water and steam space surrounding a cylindrical furnace plate surmounted by a cylindrical tube 50 plate, the tube plate having expanded into it inwardly projecting thimble tubes, a heat-resisting core hung axially along the centre line of the tube nest, together with means for raising or lowering same, and two or more sets of stepped directional plates arranged in varying pitches between the tubes in the tube nest.

6. An improved steam generator or water heater of vertical type comprising an annular water and steam space surrounding a cylindrical furnace plate surmounted by a cylindrical tube 60 plate, the tube plate having expanded into it inwardly projecting thimble tubes, a heat-resisting core hung axially along the centre line of the tube nest, together with means for raising 65

or lowering same and for cleaning the tube nest by steam or air blast, and two or more sets of plain spiralled directional plates arranged between the tubes in the tube nest.

7. An improved steam generator or water 5 heater of vertical type comprising an annular water and steam space surrounding a cylindrical furnace plate surmounted by a cylindrical tube plate, the tube plate having expanded into it inwardly projecting thimble tubes, a heat-resisting 10 core hung axially along the centre line of the tube nest, together with means for raising or lowering same and for cleaning the tube nest by steam or air blast, and two or more sets of stepped directional plates arranged in spiral fashion 15 between the tubes in the tube nest.

8. An improved steam generator or water heater of vertical type comprising an annular water and steam space formed by an outer shell 20 surrounding a cylindrical furnace plate surmounted by a cylindrical tube plate, the tube plate having expanded into it inwardly projecting thimble tubes, a heat-resisting core hung axially along the centre line of the tube nest, together with means for raising or lowering same 25 and for cleaning the tube nest by steam or air blast, plain spiralled directional plates arranged between the tubes in the tube nest, the whole of the above forming a direct fired steam generator or water heater and having arranged in integral 30 association therewith a waste gas steam generator or water heater comprising an annular water tube nest constructed of water tubes extending between vertically spaced parallel annular tube plates secured to the inside of the outer shell 35 and cylinder means joining the inner edges of these annular tube plates so that an annular gas passage is formed between the outer shell and the cylinder joining the inner edges of the 40 annular tube plates.

9. An improved steam generator or water heater of vertical type comprising an annular water and steam space formed by an outer shell surrounding a cylindrical furnace plate surmounted by a cylindrical tube plate, the tube plate having expanded into it inwardly projecting thimble tubes, a heat-resisting core hung axially along the centre line of the tube nest, together with means for raising or lowering same 45 and for cleaning the tube nest by steam or air blast, stepped directional plates arranged between the tubes in the tube nest, the whole of the above forming a direct fired steam generator or water heater and having arranged in integral 50 association therewith a waste gas steam generator or water heater comprising an annular water tube nest constructed of water tubes extending between vertically spaced parallel annular tube plates secured to the inside of the outer shell and cylinder means joining the inner edges of these 55 annular tube plates so that an annular gas passage is formed between the outer shell and the cylinder joining the inner edges of the annular tube plates.
